United States Patent Office

Des. 212,264
Patented Sept. 17, 1968

212,264

LETTER TRAY

Herbert M. Rome and Harold J. Fatt, Los Angeles, Calif.,
assignors to Eldon Industries, Inc., Hawthorne, Calif.,
a corporation of California

Filed May 18, 1967, Ser. No. 7,173

Term of patent 14 years

(Cl. D74—9)

FIG. 1.

FIG. 2.

FIG. 3.

FIG. 4.

FIG. 5.

FIGURE 1 is a top plan view of a letter tray showing our new design.

FIGURE 2 is a bottom plan view thereof.

FIGURE 3 is a front elevational view thereof.

FIGURE 4 is a rear elevational view thereof.

FIGURE 5 is a left-side elevational view thereof; the side opposite thereto presents a mirror image thereof.

The stippled area seen in FIGURE 5 represents contrast.

We claim:

The ornamental design for a letter tray, substantially as shown and described.
